MATRIX ASSEMBLING MECHANISM FOR TYPOGRAPHICAL MACHINES

Application filed December 10, 1929. Serial No. 413,074.

The present invention relates to improvements in typographical machines and more especially to those of the class shown and described in U. S. Letters Patent No. 436,532 granted September 16, 1890, to O. Mergenthaler, wherein matrices having type-forming characters therein are delivered from a magazine selectively, by manipulation of a keyboard, and assembled in a line in a so-called assembling elevator, and upon completion of each line, said elevator is lifted and the line of matrices transferred by a so-called line delivery slide from the assembling elevator to another elevator which carries the line into position in front of a mold in which a type bar or slug bearing a type face is cast against the line of matrices.

In machines of this class as heretofore constructed and used, the assembling elevator has been lifted manually by the operator after the completion of composition of each matrix line, to bring the line into position for transfer by the line delivery slide, the operation of the keyboard for the composition of matrix lines being necessarily interrupted until each matrix line, after it has been composed, has been removed from the assembling elevator and the latter has returned to its normal position, after which the operator resumed operation of the keyboard to compose the next line, and such a construction and mode of operation has the drawbacks that it not only imposes upon the operator the burden of manually lifting the assembling elevator to bring it into position for the transfer therefrom of each composed matrix line, but the interruption in the operation of the keyboard during the period the assembling elevator is removed from the matrix assembling position delays the composition of the matrices and thereby reduces the capacity or output of the machine.

The primary objects of the invention are to provide relatively simple means, utilizing largely elements already present in machines of this class, for lifting the assembling elevator by power means under control of the operator and for enabling a matrix line to be composed while the preceding line is being delivered by the assembling elevator and for

introducing the subsequently composed line into the assembling elevator upon its return to normal position, thereby enabling such machines to be operated continuously or without interruption in the composition of the matrix lines. 55

The present invention provides novel and improved means whereby the lifting of the assembling elevator to bring a composed matrix line therein into position for transfer therefrom may be accomplished by power means in which power is stored by the movement of the line delivery slide usually used in machines of this class and which may be set into operation by a key on the keyboard 60 or other means which may be readily actuated by the operator whereby the line delivery slide will be released to perform its line delivery stroke and the initial part of this stroke of the line delivery slide will store 65 the power required to lift the assembling elevator to the level to be received by the line delivery slide, the further advance of the latter on its line delivery stroke causing the matrix line to be removed from the assembling elevator and the latter to return to its normal lowered position by gravity. 70 75

The invention also provides novel and improved means which is controlled and operated by the usual line delivery slide of the machine to introduce into the assembling elevator a line of matrices composed while the assembling elevator is raised or out of normal position and novel and improved means also controlled and operated by the usual line delivery slide for supporting the foremost matrices in a succeeding matrix line undergoing composition. 80 85

To these and other ends the invention consists in certain improvements and combinations and arrangements of parts all as will hereinafter be more fully described, the features of novelty being pointed out particularly in the claims at the end of the specification. 90 95

In the accompanying drawings:—

Fig. 1 is a front elevation of the assembling elevator and line delivery slide of a typographical machine constructed in accordance with the present invention, the elevator and 190

slide being shown in the positions which they normally occupy during the composition of a line of matrices;

Fig. 2 is a view similar to Fig. 1 but showing the line delivery slide in full lines the initial part of the operative movement of the line delivery slide after its release and, by the dotted lines, a further step in the operative movement of the line delivery slide, to introduce the composed matrices into the assembling elevator and to lift the latter;

Fig. 3 is a view similar to Fig. 2, illustrating by dotted and full lines the further steps in the operative movement of the line delivery slide to commence the transfer of the matrix line therefrom while the assembling elevator is lifted;

Fig. 4 represents, partly in section, a top plan of the structure shown in Fig. 1, a portion of the structure being broken away;

Fig. 5 represents a vertical cross section taken approximately on the line 5—5 of Fig. 1 and looking in the direction of the arrows;

Fig. 6 is a top plan view on an enlarged scale, of the auxiliary matrix assembling receptacle in advance of the matrix receiving end of the assembling elevator;

Fig. 7 is a detail view representing a transverse section taken on the line 7—7 of Fig. 1 and looking in the direction of the arrows;

Fig. 8 is a perspective view of the line delivery slide and its operating connection with the assembling elevator, the parts being shown in normal position and as viewed from the front;

Fig. 9 is a detail perspective view of one end of the line delivery slide as viewed from the rear; and

Fig. 10 represents a transverse section taken on the line 10—10 of Fig. 1 and looking in the direction of the arrows.

Similar parts are designated by the same reference characters in the different views.

The present invention is applicable generally to typographical machines of the class employing an assembling elevator in which matrices delivered thereto selectively by manipulation of a keyboard are assembled therein to form a line and in which a line delivery slide or equivalent means is employed for removing the line of matrices from the assembling elevator for transfer to means which conveys the matrix line to casting position. The invention in its preferred embodiment is shown in the accompanying drawings and will be hereinafter described as applied to a typographical machine of the well known class shown and described generally in the patent hereinbefore referred to but it is to be understood that constructions equivalent to that shown are contemplated and such will be included within the scope of the claims.

Since the present invention concerns only the matrix assembling means and the means for removing or transferring the line of

matrices therefrom, the drawings have been confined to those portions of the machine, the magazine and keyboard mechanism for delivering the matrices to the assembling means and the means which receives the line of matrices delivered from the assembling means and for casting the type bars or slugs therefrom being shown and described generally in the patent hereinbefore referred to and being also well understood by those skilled in the art and familiar with machines of this class as generally constructed and used.

In the present instance, 1 represents a portion of the face plate casting which is part of the main stationary frame as commonly used in machines of this class, 2 represents the assembling elevator which is mounted to move vertically in front of the face plate, it being slideable in guides 3 and 4 and provided in its upper portion with front and rear rails 5 which form a channel between them to receive the matrices and form them in a line, 6 represents the usual assembling elevator slide finger which is movable lengthwise in the channel between the rails 5 against which the matrix line is assembled and 7 represents the assembler star wheel over which the matrices released from the magazine in the usual way by manipulation of the keyboard pass, the star wheel operating in the well known manner to stack the matrices into the line. 8 represents generally the line delivery slide which is mounted to reciprocate horizontally in a guide 9 which is fixed to the stationary face plate 1 above the assembling elevator, this slide operating to remove a line of matrices from the assembling elevator, after the latter has been lifted to its elevated position, and to transfer the matrix line to another elevator which carries the matrix line to the casting position, as is well known in machines of this class.

According to the present invention, the rails 5 of the assembling elevator are off-set to the left of the guides 3 and 4 instead of to the right thereof, as has heretofore been the practice in machines of this class, and a relatively stationary matrix assembling receptacle, composed of front and rear rails 10 which are aligned with the corresponding rails 5 on the assembling elevator when the latter is in its normal lowered position, is interposed between the right hand or matrix receiving end of the assembling elevator and the assembler star wheel 7 so that this receptacle will receive the matrices and the assembling star wheel 7 will stack the matrices in a line in this receptacle preliminarily to their introduction into the assembling elevator. The rails 10 of this receptacle are so mounted on the face plate 1 that they always remain at a constant level relatively to the assembler star wheel 7, although the front rail may be pivoted at 11 to enable it to be swung forwardly

to provide access to matrices contained within this receptacle for the insertion or removal of matrices, and it is also provided with an auxiliary rail 31 which is operatively connected to a lever 14 whereby it may be set into operative and inoperative positions to control the assembling of the matrices at different levels, this auxiliary rail corresponding with the similar rail heretofore used generally in the assembling elevator, the rails 5 of the assembling elevator having upper and lower channels to receive the matrices assembled at the different levels in the matrix assembling receptacle.

15 The line delivery slide, according to the present invention, comprises a main bar 15 having blocks 16 fixed to its ends and slidable horizontally in the guide 9, a bar 17 which is fixed to the bar 15 so that it will reciprocate in unison therewith, by the screw 18, and a matrix transfer carrier composed of the relatively long and short depending fingers 19 and 20 carried by blocks 21 and 22 which are slidable in the horizontal guide 9, these blocks being adjustably connected by a notched or graduated rod 23 which enables the fingers 19 and 20 to be locked at different distances apart to conform with matrix lines of different lengths, a pawl 24 pivotally mounted on the block 21 cooperating with the notches in the rod 23 which is attached at its other end to the block 22 and thereby holding the fingers 19 and 20 at different distances apart.

25 The bar 17 which is movable in unison with the main bar 15 of the slide is provided at its lower edge with a longitudinally elongated notch 25 in which operates a pin or projection 26 which is fixed to the block 22, so that the fingers 19 and 20 have a lost motion connection with the slide and will be picked up and shifted toward the left or the right after the bar 17 has shifted a predetermined distance in one or the other of these directions as determined by the length of the notch 25. After 40 the fingers 19 and 20 have been thus picked up by the engagement of the pin 26 with one or the other end of the notch 25, these fingers will reciprocate in unison with the bar 17. The main bar 15 is provided with a pivot 27 to 55 which the usual link connected to the lever which operates the line delivery slide is connected, it being common and well known in machines of this class that the operating lever for the line delivery slide is actuated to shift the slide in a direction to remove the matrix line from the assembling elevator and transfer it to the elevator which carries the line to the casting position, by a spring controlled usually by an air cushion, and which a cam on the 60 machine operates at an appropriate time in the cycle of operations of the machine, to return the line delivery slide to its normal or retracted position such as that shown in Fig. 1. Since the usual and well known operating means may be used to operate the line delivery

slide provided by the present invention, it is deemed unnecessary to illustrate such operating means herein.

The introduction of the matrices assembled in the auxiliary assembling receptacle into the assembling elevator and the control of the matrices assembled in the auxiliary receptacle while the assembling elevator is in raised position are effected by a pair of fingers 28 and 29 respectively, these fingers being pivotally suspended from a pin 30 which projects forwardly from a rotatable disk 31, the latter being rotatably mounted on a pivot pin 32 supported by a bracket 33, the latter being fixed to the stationary face plate 1. A coiled friction spring 31^a encircles the pivot pin 32 and seats in counterbored recesses in the front face of the disk 31 and the rear face of the bracket 33, the friction produced by this spring being sufficient to prevent rotation of the disk under the weight of the fingers 28 and 29 while in their normal raised position shown in Fig. 1, so that the disk will remain in its normal position until it is rotated out of such position by the action of the line delivery slide, as hereinafter described. The fingers 28 and 29 are mounted directly above the matrix receiving channel formed between the rails 10 of the auxiliary assembling receptacle, and when the disk 31 occupies its normal position shown in Fig. 1, the upper ends of these fingers will be immediately above the path of the tops of matrices in the auxiliary assembling receptacle. The finger 29 has a spring 34 connected to it above the pivot pin 30 and acting in a direction to hold the pin 35 thereon yieldingly against a relatively fixed stop, such as a vertical edge of the usual relatively fixed space band chute 35^a, so that the lower end of this finger will be directly above the entrance end of the auxiliary matrix assembling receptacle, and the friction spring 31^a acting on the disk 31, will normally hold said disk in the position shown in Fig. 1. The lower end of the finger 29 is preferably provided with a hinged plate 36 which is adapted to remain in vertical position so that it will bear flatwise against a matrix in the auxiliary assembling receptacle during 100 swinging movement of the finger 29 about the pivot pin 30, as indicated by the dotted lines in Fig. 2, the finger 29 being lowered into the matrix receiving channel of the auxiliary matrix assembling receptacle when the disk 31 is rotated in a clockwise direction which 105 acts to lower the pivot pin 30, as will be clear from Fig. 2, and the matrices introduced into the auxiliary matrix assembling receptacle by the revolving assembler star wheel 7 will cause the finger 29 to swing toward the left as indicated by the dotted lines in Fig. 2, the lower pivoted end 36 on the finger 29 resting against the foremost matrix in the matrix line 110 designated M and being advanced toward the 115

left as the matrices are stacked into the receptacle by the star wheel 7.

The finger 28 is provided at its upper end with a block 37 which extends above the pivot 30 and is arranged to bear on a nose 38 formed on the bracket 33, this nose forming an abutment which will obstruct the movement of the block 37 as the disk 31 rotates in a direction to lower the pivot 30, so that as the disk rotates in such direction, the finger 28, after it has been lowered directly to engage the rearmost matrix in a line composed in the auxiliary assembling receptacle, will swing about the pivot 30 from the full line position to the dotted line position shown in Fig. 2, and during such swinging movement of the finger 28 the lower end thereof sweeps through the matrix channel between the rails 10 of the auxiliary assembling receptacle and thereby removes the line of matrices from said receptacle and introduces them into the matrix channel between the jaws 5 of the assembling elevator as represented by the dotted lines in Fig. 2.

25 The assembling elevator 2 is normally locked in its lower line receiving position by a latch 39 which is pivoted at 40 to a plate 41, the latter being fixed to the stationary face plate 1, the latch having at one end a toe 42 arranged to engage the upper side of a lug or projection 43 formed on the rear side of the rear assembling elevator rail 5, a spring 44 being connected at one end to the latch 39 and at its other end to a pin 45 on the stationary face plate 1 and acting to normally hold the latch in engagement with the lug 43. A stop 46 on the stationary plate 41 serves to arrest the swing of the latch under the action of the spring 44, this stop holding the latch 43 in position to receive the lug or projection 43 beneath the toe 42, as shown in Fig. 1, when the assembling elevator moves into its normal lowered position. The upper end of the latch 39 has a forwardly extending finger 47 thereon which lies in the path of the finger 28 so that when the latter approaches the end of its swinging movement under the action of the nose 38, it will swing the latch from the full line position shown in Fig. 2, in which it locks the assembling elevator in lowered position, into the dotted line position shown in that figure, thereby unlocking or releasing the assembling elevator so that it may rise.

55 The disk 31 is rotated to carry the fingers 28 and 29 from their normal raised position as shown in Fig. 1 to their lower operative position as shown in Fig. 2 during the initial part of the movement of the line delivery slide to transfer a matrix line from the auxiliary assembling receptacle to the assembling elevator and to subsequently remove the matrix line from the assembling elevator. To accomplish this, a pawl 48 is pivotally connected by a pivot pin 49 to the bar 17 of the line delivery slide, this pawl being gravity

operated and normally resting in the position shown in Fig. 1, its movement being limited by a pin 50 on the pawl which operates in a slot 51 in the bar 17, and the disk 31 has a pin 52 fixed to it and projecting rearwardly from its rear face so that it lies adjacent to and in the path of the free end of the pawl 48 when the bar 17 is in its normal fully retracted position. In consequence, the pin 52 will be engaged by the pawl 48 at the commencement of the forward or operative movement of the bar 17 and as the latter continues its operative movement, the disk 31 is caused to rotate from the normal position shown in Fig. 1, in a clockwise direction into the successive positions shown by the full and dotted lines in Fig. 2, and during the latter part of the movement of the pin 52 under the action of the pawl 48, the pin 52 reaches and rides upon the upper side of the pawl 48 which occupies an inclined position, the pawl 48 being supported during this operation by the pin 50 which engages the bottom of the slot 51, the pin 52 eventually reaching a position substantially level with the pivot 32 of the disk 90 as the pawl 48 passes beneath the pin 52 during the continued operative stroke of the bar 17. The disk 31 has a second pin 53 projecting from its rear side, and this pin is brought, by the rotation of the disk 31 to lower the fingers 28 and 29 and to swing the finger 28 to effect the line transfer operation, into a position in the path of an inclined cam surface 54 on the bar 17, and this cam surface acts on the pin 53, during the continued stroke 100 of the bar 17, to rotate the disk 31 back to its normal position, as illustrated diagrammatically by the full and dotted lines in Fig. 3, and as the stroke of the bar 17 continues in the same direction, the pin 53 is received in a groove 55 which extends longitudinally in the bar 17, the disk 31 being thereby locked in its normal position during the rest of the stroke of the bar 17. The return of the disk 31 to normal position restores the fingers 28 110 and 29 to their normal raised position clear of the path of the matrices, as shown in Fig. 1.

The assembling elevator 2 is lifted from its lower matrix receiving position shown by the matrix delivery position as shown by the dotted lines in said figure, by a lever 56 one end of which is pivotally connected to a link 57 which link in turn is pivotally connected to a pin 58 on the rear side of the assembling elevator and the other end of said lever is pivotally connected to the face plate 1 by the pivot pin 59 about which said lever swings as a center. The main bar 15 of the line delivery slide has a gravity acting pawl 60 pivotally connected to it by a pivot pin 61, this pawl being normally supported in an inclined position by a stop pin 62 fixed to the bar 15 and engaging a lug 63 on the pawl. A lever 64 is pivotally mounted on the lever 130

56 by a pivot pin 65, one end of this lever 64 carrying a roller or projection 66 which is in the path of the inclined upper side of the pawl 60 and the other end of this lever 64 is connected to one end of a tension spring 67 the opposite end of which is attached by the projection 68 to a plate 69 at a point above the pivot 59, the plate 69 being freely rotatable on the pivot 59, and the plate 69 has a 10 projection 70 thereon located below the pivot 59 and to which a tension spring 71 is attached, the opposite end of this spring being fixed at 72 to the stationary face plate 1. The end of the lever 64 on which the tension 15 spring 67 acts, normally rests against a stop pin 73 on the plate 69. The tension spring 71 is a counterbalance spring, it acting on the lever 56, through the plate 69, spring 67 and lever 64 to lift the lever 56 and the assembling 20 elevator to which it is connected, but the spring 71 is of insufficient power to lift the assembling elevator or to maintain it in elevated position, so that the assembling elevator will be able to descend against the action 25 of the spring 71, except when the tension of the spring 67 is increased, which is effected by the riding of the roller or projection 66 up the inclined upper side of the pawl 60 as the delivery slide moves from the position shown in Fig. 1 to and through the 25 positions shown by the full and dotted lines in Fig. 2 during which the lever 64 is rocked relatively to the lever 56 about the pivot 65 and in a direction to increase the tension of 30 the spring 67, the latter acting in a direction to lift the assembling elevator from the full line position shown in Fig. 2 to the dotted line position shown in that figure. As the movement of the line delivery slide continues 35 in the same direction, the pawl 60 which moves with it, passes beneath the roller or projection 66, thereby permitting the lever 64 to resume its normal relation with the lever 56 and thereby reducing the tension of the 40 spring 67.

When the elevator reaches the limit of its upward movement, it engages the free end of a pawl 74 which is pivoted at 75 on the stationary frame and the opposite end of 45 which engages the block 22 of the short matrix line engaging finger 20 thereby releasing the line delivery slide so that it may continue its movement in a direction to remove the matrix line from the assembling elevator, 50 and when the assembling elevator reaches its elevated position, a latch 76 thereon engages a dog on the stationary frame and locks the assembling elevator in its proper raised position, and when the line delivery slide has 55 reached a position in its operative movement where the matrices have been removed from the assembling elevator, this latch is engaged and tripped by the block 22 of the short 60 matrix line engaging finger 20, and the assembling elevator is then free to descend to 65

its normal lowered position. Since the construction and operation of the pawl 74 and latch 76 are well known in machines of this class, further illustration and description thereof is deemed unnecessary.

The line delivery slide is held in its normal retracted position as shown in Fig. 1 by a key rod 77 the upper end of which is engageable in a notch 78 in the lower edge of the bar 17 when the line delivery slide is fully retracted, the lower end of this key rod being operatively connected to a key lever 79 which is pivoted at 80 to a side or other part of the usual keyboard 81 which contains the keys and their mechanism for controlling the delivery of matrices from the magazine, the key lever 79 having a button 82 thereon which is within convenient reach of the operator occupying his usual position in front of the keyboard, depression of the button 82 serving to trip or release the line delivery slide and to set it into operation. A spring 83 attached to the key lever 79 acts thereon to maintain the upper end of the key rod 77 against the lower edge of the bar 17 so that the upper end of the key rod 77 will be normally held in engagement with the locking notch 78 while the line delivery slide is in its normal position and it will be automatically re-engaged with this notch when the line delivery slide is restored to its normal position.

The mode of operation of matrix assembling means constructed in accordance with the present invention, is as follows:—The matrices are selectively delivered from the usual magazine by manipulation of the keyboard, thus bringing the matrices over the revolving assembler star wheel 7 in the usual manner, but the matrices, instead of being received directly by the assembling elevator, as heretofore, are received in the auxiliary assembling receptacle which is located in advance of the matrix receiving end of the assembling elevator, they being stacked in a line in the auxiliary matrix assembling receptacle. At this time, the assembling elevator 2 is in its lowered position aligned with the auxiliary matrix assembling receptacle and the line delivery slide is in its normal retracted position, as shown in Fig. 1, the fingers 28 and 29 being raised clear of the path of the assembling matrices. After a sufficient number of matrices have been supplied to the auxiliary assembling receptacle to form a line of the predetermined length, the operator depresses the key lever 79 thereby disengaging the upper end of the key rod 77 from the notch 78 in the bar 17 of the line delivery slide and thereby releasing this slide so that it may move toward the left from its normal position shown in Fig. 1.

The initial part of the operative movement of the line delivery slide, which involves a movement of the bars 15 and 17 toward the

left while the fingers 19 and 20 remain stationary due to the engagement of the pin 26 on the finger 20 in the elongated notch 25 in the lower edge of the bar 17, causes the pawl 48 on the bar 17 to act on the pin 52 on the rear side of the disk 31 to rotate the latter in a clockwise direction. The first part of this rotation of the disk 31, which brings it into the full line position shown in Fig. 2, 5 lowers the fingers 28 and 29 into a position between the last matrix introduced into the line and the assembler star wheel 7. The finger 29 serves to separate the matrices in the line of composed matrices from matrices subsequently delivered to form the next succeeding line, and the operator of the machine may 10 continue without interruption the manipulation of the keyboard to compose the matrices which are to form the next succeeding line, 15 the matrices of the latter line being separated from those of the previously composed line by the interposed plate 36 at the lower end of the finger 29. Further movement of the bar 17 toward the left during the operative 20 travel of the line delivery slide causes the pawl 28 to act on the pin 52 to rotate the disk 31 into the position shown by the dotted lines in Fig. 2, and while the disk is rotating into this position, the finger 28, which has been 25 previously lowered into a position behind the matrix line already composed, is caused to swing, by the action of the nose 38 on the block 37, from the full line position to the dotted line position shown in Fig. 2, this 30 finger 28 being thus swung through the matrix channel between the rails 10 of the auxiliary assembling receptacle and sweeping the already composed matrix line out of said receptacle and into the assembling elevator, 35 this matrix line coming against and pushing the usual assembler slide finger 6 ahead of it. The matrix line thus removed from the auxiliary assembling receptacle is brought into a 40 position to be received between the fingers 19 and 20 of the line delivery slide.

The travel of the line delivery slide from the normal position shown in Fig. 1 to the full and dotted line positions shown in Fig. 2 also causes the inclined pawl 60 to ride beneath the roller or projection 66 on the lever 64, thereby swinging this lever relatively to the main elevator lifting lever 56 and thus increasing the tension of the spring 67 to store energy therein to lift the assembling 55 elevator and while energy is being thus stored in the springs 67, the finger 28 reaches the arm 47 on the latch 39 and swings said latch in a direction to release the assembling elevator whereupon the latter is elevated by 60 the energy stored in the spring 67 and is locked in its elevated position by the latch 76 which latch operates in the manner usual in machines of this class. The ascent of the assembling elevator also trips the pawl 74 65 which normally locks the fingers 19 and 20

against movement, it being understood that these fingers remain motionless during the initial travel of the bar 17 which operates the fingers 28 and 29 and releases the assembling elevator, due to the engagement of the pin 26 on the finger 20 in the longitudinally elongated notch 25 in the lower edge of the bar 17, but after the right hand end of the notch 25 has reached the pin 26, the finger 20 and also the finger 19 connected to it by the rod 23 are picked up by the line delivery slide and thereafter move in unison with it, these fingers 19 and 20, which receive between them the matrix line lifted by the assembling elevator, operating during the continued operative movement of the line delivery slide, to remove such matrix line from the assembling elevator and to convey it in the manner usual in machines of this class to another elevator which conveys the matrix line to the casting position.

The continued operative movement of the line delivery slide immediately following the swing of the finger 28 to introduce the matrix line into the assembling elevator and to trip the latch 39 brings the cam surface 54 on the bar 17 against the pin 53 on the disk 31 and causes the disk to rotate back to its normal position as shown diagrammatically by the full and dotted lines in Fig. 3, thereby lifting the fingers 28 and 29 and restoring them to their normal raised position clear of the path of the assembling matrices, the disk 31 being locked in this position by the engagement of the pin 53 in the groove 55 in the bar 17, and since the latch 76 on the assembling elevator is tripped by the finger 20 as soon as the matrix line has been removed from the assembling elevator, the latter descends by gravity against the action of the lifting spring 67 the tension of which is then reduced by the passing of the pawl 60 beyond the roller 66, so that the assembling elevator is restored immediately to a position to receive the next matrix line which has, in the meantime, been in the course of assembly in the auxiliary assembling receptacle by the continued or interrupted operation of the matrix delivery keys of the keyboard by the operator, and the assembler slide finger 6 in the assembling elevator will be thus brought into position to receive such line.

The pawls 48 and 60 pass beneath and beyond the projection 52 and roller 66 respectively while the line delivery slide is completing its operative movement, and during the return stroke of the line delivery slide to its normal retracted position, the pawl 48 rides idly over the pin 52 and the pawl 60 rides idly over the roller 66, and during the return movement of the line delivery slide, the left hand end of the notch 25 in the lower edge of the bar 17 engages the pin 26 connected to the finger 20 and thereby draws the fingers 19 and 20 back to their normal po-

sition as shown in Fig. 1, and when the line delivery slide reaches its fully retracted position, it is automatically locked in such position by the re-engagement of the upper 5 end of the key rod 77 in the notch 78 in the lower edge of the bar 17. The line delivery slide is then ready to be again released or tripped by depression of the key lever 79 immediately upon completion of 10 the matrix line in course of composition, whereupon the cycle of operations hereinbefore described will be repeated.

The present invention thus accomplishes the dual result of lifting the assembling elevator by power stored in a spring by the operative movement of the usual line delivery slide commonly used in machines of this class, it being merely necessary for the operator to depress a finger key on or adjacent 20 to the usual keyboard in order to release the line delivery slide and thereby set the assembling elevator lifting mechanism into operation upon completion of the composition of a matrix line, and of transferring a succeeding 25 line of matrices composed in the auxiliary assembling receptacle to the assembling elevator after the latter has been returned to its normal lowered position by gravity, by the fingers which are also operated by the movement of the usual line delivery slide, and such utilization of the usual line delivery slide enables continuous or uninterrupted composition of the matrix lines to be performed in a machine of relatively 30 simple construction.

The matrix assembling mechanism provided by the present invention is applicable to typographical machines of the general class hereinbefore referred to without requiring 40 modification of the other mechanisms of the machine, since the modified assembling elevator and its cooperating auxiliary assembling receptacle may replace the usual assembling elevator and may receive the matrices delivered by the usual means from the magazine under control of the usual keyboard, and the modified line delivery slide may replace the usual line delivery slide and may be operated by the same means usually employed for operating the line delivery slide heretofore commonly used, the construction of the modified line delivery slide being such however that the initial part of 50 its operative movement will effect the transfer of the matrix line from the auxiliary assembling receptacle to the assembling elevator and the lifting thereof, and the further operative movement of the line delivery slide will cause the matrix line engaging fingers 55 to be picked up and to advance with the slide to remove the matrix line from the assembling elevator.

I claim as my invention:

1. In a typographical machine, an assembling elevator movable upwardly from a

matrix receiving position to a matrix discharging position, a slide for removing matrices from said elevator while the latter is lifted, means operative by movement of said slide in the matrix removing direction to store power to lift the elevator, and key-controlled means for setting said slide into operation.

2. In a typographical machine, an assembling elevator movable from a matrix receiving position upwardly to a matrix discharging position, a slide for removing matrices from said elevator, spring means operative by movement of said slide in the matrix removing direction to store power to lift the elevator, and manually-controlled releasing means for setting said slide and spring means into operation to lift the elevator.

3. In a typographical machine, an assembling elevator movable from a matrix receiving position upwardly to a matrix discharging position, a slide for transferring matrices from the elevator while the latter is in the matrix discharging position, power means operative by movement of said slide in the matrix transferring direction to store power to lift the elevator, and releasing means controlled by movement of said slide in the matrix transferring direction for setting the power means into operation.

4. In a typographical machine, an assembling elevator movable upwardly from a matrix receiving position to a matrix discharging position, a matrix line delivery slide embodying means having a lost motion connection therewith for discharging matrices from the elevator, a lever connected to the elevator for lifting it into matrix discharging position, and spring means interposed between said lever and slide and actuated by the initial part of the movement of the latter in the matrix discharging direction to lift the elevator.

5. In a typographical machine, an assembling elevator movable upwardly from a matrix receiving position to a matrix discharging position, a matrix line delivery slide for discharging matrices from the elevator, a lifting lever for the elevator, a spring-tensioned member connected to said lever, and means connected to the slide and acting on said member during the initial part of the movement of said slide in the matrix discharging direction to increase the spring tension on said member and thereby lift the elevator and to relax such tension during the further movement of the slide in the same direction.

6. In a typographical machine, a vertically movable assembling elevator, a horizontally reciprocatory matrix line delivery slide for removing matrices from the elevator, a lifting lever for the elevator, a pivoted member, a lever pivoted on said lifting lever and having a projection at one end, a lifting spring connecting the other end of said lever

on the lifting lever to said member at one side of its pivot, a counterbalancing spring connected to said member at the other side of its pivot, and a pawl pivotally connected to said 5 slide and having an inclined surface to act on said projection to increase the tension of said lifting spring.

7. In a typographical machine, an assembling elevator movable into matrix line receiving and discharging positions, a line delivery slide for removing a matrix line from 10 said elevator, a receptacle for assembling matrices in advance of their reception by said elevator, and means controlled by said 15 slide for transferring matrices from said receptacle to the assembling elevator.

8. In a typographical machine, an assembling elevator movable into matrix line receiving and discharging positions, a member 20 for removing a matrix line from said elevator, an auxiliary matrix assembling receptacle mounted in a position to deliver matrices therefrom to the assembling elevator 25 while the latter is in matrix line receiving position, and means operated by said matrix line removing member for transferring matrices assembled in said receptacle from the latter to the assembling elevator.

30 9. In a typographical machine, an assembling elevator movable into matrix line receiving and discharging positions, a member for removing a matrix line from said elevator, an auxiliary matrix assembling receptacle 35 mounted in a position to deliver matrices therefrom to the assembling elevator while the latter is in matrix line receiving position, and a finger movable longitudinally in said receptacle by the operation of said 40 member and operative to transfer matrices assembled therein to the assembling elevator.

10. In a typographical machine, an assembling elevator movable to and from matrix line receiving position, means for removing 45 a matrix line from said elevator, an auxiliary matrix assembling receptacle positioned to transfer matrices therefrom to the elevator while the latter is in matrix receiving position, a finger movable in said 50 receptacle by the operation of said matrix line removing means and operative to transfer matrices assembled in said receptacle to said elevator, and a second finger also movable in said receptacle and against which matrices 55 assembled in rear of the first-mentioned finger are stacked.

11. In a typographical machine a matrix assembling elevator movable into matrix receiving and discharging positions, auxiliary 60 matrix assembling means positioned to deliver matrices assembled therein to the elevator while the latter is in matrix receiving position, a matrix line delivery slide for removing matrices from the elevator while the latter is in matrix discharging position, and

a matrix transferring member actuated by said slide and movable in said auxiliary matrix assembling means to transfer matrices assembled therein to the elevator.

12. In a typographical machine, a matrix 70 assembling elevator movable into matrix receiving and discharging positions, an auxiliary matrix assembling receptacle positioned to discharge matrices therefrom into the elevator while the latter is in matrix receiving position, a line delivery slide operative to remove a matrix line from the elevator while the latter is in matrix discharging position, and means operative by said slide to transfer matrices assembled in said receptacle to the elevator. 75

13. In a typographical machine, a matrix assembling elevator movable into matrix receiving and discharging positions, auxiliary 80 matrix assembling means positioned to discharge matrices assembled therein to said elevator while the latter is in matrix receiving position, a line delivery slide for removing matrices from said elevator while the latter is in matrix discharging position, a matrix transfer finger, and means operative by said slide for moving said finger through said auxiliary assembling means to transfer matrices assembled therein to the elevator. 85

14. In a typographical machine, a matrix 90 assembling elevator movable into matrix receiving and discharging positions, auxiliary matrix assembling means positioned to discharge matrices assembled therein to the elevator while the latter is in matrix receiving 100 position, a line delivery slide having matrix engaging means for removing a matrix line from the elevator while the latter is in matrix discharging position, a matrix transfer member, and operating means for said member actuated by the slide and operative to introduce said member into the auxiliary assembling means and to move it therein to transfer matrices assembled in said auxiliary assembling means to the elevator. 105

15. In a typographical machine, a matrix assembling elevator movable into matrix receiving and discharging positions, auxiliary matrix assembling means positioned to discharge matrices assembled therein to the elevator while the latter is in matrix receiving position, a line delivery slide including matrix engaging means having a lost-motion connection therewith and operative to remove matrices from the elevator while the latter is in matrix discharging position, a matrix transfer member, and means actuated by the movement of the slide prior to the commencement of the matrix removing movement of the matrix engaging means for moving said transfer member through the auxiliary assembling means to transfer matrices therefrom to the elevator. 115

16. In a typographical machine, a matrix 120 assembling elevator movable into matrix receiving and discharging positions, auxiliary matrix assembling means positioned to discharge matrices assembled therein to the elevator while the latter is in matrix receiving position, a line delivery slide including matrix engaging means having a lost-motion connection therewith and operative to remove matrices from the elevator while the latter is in matrix discharging position, a matrix transfer member, and means actuated by the movement of the slide prior to the commencement of the matrix removing movement of the matrix engaging means for moving said transfer member through the auxiliary assembling means to transfer matrices therefrom to the elevator. 125

ceiving and discharging positions, auxiliary matrix assembling means positioned to discharge matrices therefrom to the elevator while the latter is in matrix receiving position, a line delivery slide for removing matrices from the elevator while the latter is in matrix discharging position, a rotatable member, a finger pivotally suspended therefrom, and means carried by said slide and engageable with said member to rotate it and thereby swing said finger into the auxiliary assembling means to act on matrices therein.

17. In a typographical machine, a matrix assembling elevator movable upwardly from matrix receiving position into matrix discharging position, auxiliary matrix assembling means positioned to discharge matrices assembled therein to the elevator while the latter is in matrix receiving position, a line delivery slide operative to remove matrices from the elevator while the latter is in matrix discharging position, matrix transfer means operative by said slide to transfer matrices from the auxiliary assembling means to the elevator while the latter is in matrix receiving position, and elevator lifting means operative by said slide to lift the elevator to matrix discharging position.

18. In a typographical machine, a matrix assembling elevator movable upwardly from matrix receiving position into matrix discharging position, lifting means for the elevator, a latch holding the elevator in its lower matrix receiving position, auxiliary matrix assembling means positioned to discharge matrices therefrom to the elevator while the latter is in the lower position, a matrix transfer member movable through said auxiliary assembling means to transfer matrices therefrom to the elevator while the latter is in its lower position and to engage and release said latch, a line delivery slide for removing matrices from the elevator while the latter is in the upper matrix discharging position, and means actuated by said slide for operating said matrix transfer member and said elevator lifting means.

19. In a typographical machine, a matrix assembling elevator movable upwardly from a lower matrix receiving position to an upper matrix discharging position, spring actuated means for lifting the elevator, a latch for holding the elevator in its lower matrix receiving position, auxiliary matrix assembling means positioned to align with the elevator while the latter is in its lower matrix receiving position, a matrix transfer finger, means operative to introduce said finger into the auxiliary assembling means and to move it therein to transfer matrices therefrom to the elevator and into engagement with said latch to release it, a line delivery slide for receiving matrices from the elevator while the latter is in its upper matrix discharging position, and means operated by said slide for

actuating said finger and the spring actuated elevator lifting means.

20. In a typographical machine, a matrix assembling elevator movable upwardly from a lower matrix receiving position to an upper matrix discharging position, lifting means for the elevator, a latch for holding the elevator in its lower position, auxiliary matrix assembling means positioned to discharge matrices therefrom into the elevator while the latter is in the lower position, a member movable in said auxiliary assembling means to transfer matrices therefrom to the elevator and engageable with said latch to release it, a line delivery slide including matrix engaging means having a lost-motion connection therewith for removing matrices from the elevator while the latter is in its upper position, and means operative by said slide during the initial part of its movement and before the movement of the matrix engaging means thereon commences for actuating said matrix transferring and latch releasing member and the elevator lifting means.

In testimony whereof I have hereunto set my hand.

SAMUEL E. SPERRY.
